United States Patent Office

Des. 224,622

Patented Aug. 15, 1972

224,622

CLOCK

Carl-Gerhard Wennermo, 22 Nygatan,
71300 Nora Stad, Sweden

Filed Apr. 28, 1971, Ser. No. 138,400

Term of patent 14 years

Int. Cl. D10—01

U.S. Cl. D42—7

FIG. 1.

FIG. 2.

FIG. 1 is a front elevational view of a clock showing my new design;

FIG. 2 is a left side elevational view, the opposite side being a mirror image thereof.

I claim:

The ornamental design for a clock, as shown and described.
